UNITED STATES PATENT OFFICE.

CHRISTINA WILSON RICHERT, OF BUFFALO, NEW YORK.

NECKBAND-HOLDER.

No. 845,979.

Specification of Letters Patent.

Patented March 5, 1907.

Application filed November 1, 1905. Serial No. 285,422.

To all whom it may concern:

Be it known that I, CHRISTINA WILSON RICHERT, a citizen of the United States, residing at Buffalo, in the county of Erie and 5 State of New York, have invented a new and useful Improvement in Neckband-Holders, of which the following is a specification.

This invention relates to a distender or holder which is more particularly designed 10 for spreading the stocks or bands worn by ladies about the neck, but which may also be used for other purposes.

The object of this invention is the production of a reliable and efficient holder of this 15 character which can be produced at small cost and which can be readily applied to or removed from the parts to be held in a distended position.

In the accompanying drawings, Figure 1 20 is a perspective view showing my improved holder applied to a stock or neckband. Fig. 2 is a detached front view of the holder on an enlarged scale. Fig. 3 is a fragmentary sectional view showing the manner in which the 25 holder is attached to the neckband.

Similar letters of reference indicate corresponding parts throughout the several views.

My improved neckband-holder is preferably bent from a single piece of wire, although the same may be otherwise constructed, if desired.

In its general construction the holder consists of a main longitudinal bar or body A A', spurs B B', arranged lengthwise adjacent to opposite ends of the bar, and each provided with a pointed outer end, and guards C C', arranged adjacent to the points of the spurs. At its opposite outer ends the bar is provided with laterally-projecting arms d, and 40 the adjacent inner ends of the spurs are provided with similar arms e, which project laterally in a direction opposite to that of the bar-arms d. The guards C C' have the form of outwardly-curved bows or arches, and each guard is connected at its ends with the outer ends of the adjacent spur and bar arms, while its central part is arranged on the side of the pointed outer end of the respective spur. The relative position of each 45 guard and the adjacent spur is such that the point of the spur engages with the side of the guard, but stops a short distance inside of the periphery of the guard. By this means the point of the spur is exposed sufficiently to 50 permit of readily sticking the same through the fabric of the neckband, but protection is

afforded against sticking the flesh of the neck or the hands, as would be the case if the guard extended beyond the end of the spur-point.

In using my improved holder the same is applied transversely to the neckband by engaging the spurs at its opposite ends with the neckband near its upper and lower edges. When the holder is thus applied to the neckband, parts of the latter are confined on the spurs between the guards and the arms of the spurs, whereby the holder is securely held on the neckband, and the latter is reliably held in a spread or distended condition.

The arms of the spurs are preferably bent at right angles thereto, so as to form comparatively sharp or abrupt corners between the same, as shown in the drawings. These arms thus form stops or shoulders against 75 which the material of the neckband, which is pierced by the spurs, abuts or rests and is prevented from working or sliding around the corners to the spur-arms, which otherwise would be possible if the corners were rounded. 80

In order to facilitate the application of the holder to the neckband, the bar is constructed in two sections A A', the inner opposing ends of which are yieldingly connected by two spring-loops f f'. The latter project in 85 opposite directions from the bar-sections in the same plane as the guards and have their inner ends connected with each other, while their outer ends are connected, respectively, with the inner ends of the bar-sections, as 90 shown in Figs. 1 and 2.

After one of the spurs has been stuck into the neckband the bar is contracted somewhat in length, thereby compressing the spring-loops, and while in this position the other 95 spur is stuck into the neckband. Upon now releasing the bar-sections and permitting the spring-loops to expand the two spurs are moved outwardly in opposite directions from each other and hold the neckband perfectly smooth in a spread position.

My improved holder is applicable either to the inside or the outside of the neckband with equal effect and without danger of scratching the neck by the points of the 105 spurs.

When the holder is intended for exclusive use on the outer side of the neckband, the same may be suitably jeweled or ornamented, so as to render the same more attractive, 110 although the same presents a neat appearance without any additional ornamentation.

I claim as my invention—

1. A neckband-holder comprising a bar, a spur arranged at the end of the bar and having a pointed outer end, and a bow-shaped guard arranged with its central part along the side of the point of the spur, substantially as set forth.
2. A neckband-holder comprising a bar having a laterally-projecting arm at its end, a spur arranged adjacent to the end of said bar and having a pointed outer end and provided at its inner end with an arm which projects laterally in a direction opposite to the arm of said bar, the inner ends of said arms being opposite each other but unconnected, and a bow-shaped guard connected at its ends with the outer ends of said arms and having its central part arranged adjacent to the pointed end of said spur, substantially as set forth.
3. A neckband-holder comprising a longitudinal bar provided at opposite ends with laterally-projecting arms, longitudinal spurs arranged adjacent to the ends of said bar and each having a pointed outer end and an arm at its inner end which projects laterally in a direction opposite to the adjacent arm of said bar, the inner ends of the corresponding bar-arm and bow-arm being opposite each

other but unconnected, and bow-shaped guards each of which is connected at its ends with the outer ends of the arms of one spur and the adjacent end of the bar and having its central part arranged adjacent to the pointed end of the adjacent spur, substantially as set forth.

4. A neckband-holder comprising a longitudinal bar provided at opposite ends with laterally-projecting arms and at its central part with oppositely-projecting loops which form a spring, longitudinal spurs arranged adjacent to the ends of said bar and each having a pointed outer end and an arm at its inner end which projects laterally in a direction opposite to the adjacent arm of said bar, and bow-shaped guards each of which is connected at its ends with the outer ends of the arms of one spur and the adjacent end of the bar and having its central part arranged adjacent to the pointed end of the adjacent spur, substantially as set forth.

Witness my hand this 30th day of October 1905.

CHRISTINA WILSON RICHERT
